UNITED STATES PATENT OFFICE.

FRANK M. GILHAM, OF SAN FRANCISCO, CALIFORNIA.

DESIGN FOR A RIDING-SADDLE.

SPECIFICATION forming part of Design No. 35,329, dated November 26, 1901.

Application filed March 14, 1901. Serial No. 51,207. Term of patent 7 years.

To all whom it may concern:

Be it known that I, FRANK M. GILHAM, a citizen of the United States, residing in the city and county of San Francisco, in the State 5 of California, have invented and produced a new and original Design for a Riding-Saddle, of which the following is a specification, reference being had to the accompanying drawing, forming part thereof, the same being a 10 side elevation of a riding-saddle showing my new design.

As shown in the drawing, the leading or material features of my design consist of a riding-saddle of the Mexican type having on the 15 edge or margin of the basto or skirt *a* the front jockey *c*, the rear jockey *d*, the middle jockey *e*, the sudadero or leg-fender *f*, a tapadero or stirrup-cover *g*, and a scalloped edge and ornamental border. These scallops ex-

tend along the bottom edge of the basto and 20 are returned at the ends and carried up on the front and rear edges, as seen at *b* in the drawing. The edges of the front jockey *c*, rear jockey *d*, and middle jockey *e* are ornamented with scallops in like manner, and the 25 same are carried down and around the edges of the leg-fender and stirrup-cover *g*, as shown.

Having thus described my invention, what I claim as new, and desire to secure by Letters Patent, is—

The design for a riding-saddle as herein shown and described.

In testimony that I claim the foregoing I have hereunto set my hand and seal.

FRANK M. GILHAM. [L. S.]
